ROLLER SKATE

Raphael Cledina, Liege, Belgium

Application June 9, 1934, Serial No. 729,888
In Belgium June 17, 1933

4 Claims. (CL. 280—11.20)

This invention has for its object to realize a roller skate having steering and braking devices and permitting a parallel running of the skates similar to that known by ski-running.

5 The invention will be described with reference to the accompanying drawings, in which:

Figure 1 is a plan view of a roller skate; Figure 2, a side elevation and Figure 3, a front view of the same; Figure 4, a partial front view of the steering device after action; Figure 5, a side elevation of the roller skate in a modified form; Figure 6, a front view of the same; Figure 7, a side elevation of the roller skate in a further modified form and Figure 8 a plan view of the same.

Referring to the drawings, the frame 1 of the roller skate is preferably made of sheet metal, which is bent to form two branches 1a, 1b, supported by the axle 2 of the back wheel 3, which is provided with rubber tyres. The frame 1 may be made also of a slight cast metal.

The back wheel 3 is arranged by means of a suitable known device so as to be prevented from running backwards, but only forwards; for example by means of a ratchet wheel 3a secured to the back wheel and acted on by a spring controlled pawl 3b.

Cross bars 4 are fitted to the front part of the frame 1 and they carry a supporting plate 5 of conventional design to which the boot is secured by means of well known fastening devices, such as clamps 5a. The supporting plate 5 is pivoted around a pin 6 connecting the frame branches 1a, 1b towards the heel portion of the plate. The back wheel axle 2 is provided with a brake drum 7 surrounded by a brake band 8 connected at 8a by conventional means to the rear end of the supporting plate 5.

At its front part, the frame 1 is provided with 40 a rod 16 which forms an extension thereof the frame 1 being pivotally connected at 8, 8' and 8'' to a longitudinal rod 10 extending towards the fore wheel axle 13 to form a bearing 11 for a vertical pin 12 carried by the said axle 13. The pin 12 is formed integral with or fixed to a toothed segment 14 which engages with a second toothed segment 15 carried by the forked end 16' of the rod 16.

By using the described roller skate, the skater 50 does not go forward by swaying from one side to the other as is known with ordinary roller skates but rather he advances by ski-running and by maintaining the skates parallel to one another, the skates being prevented by the ratchet wheel 55 from running back.

If the skater wishes to change the direction of his run, he presses the plate 5 to one side causing the frame 1 to pivot laterally around the rod 10 towards the desired side thereby causing the toothed segment 15 to rotate the toothed segment 5 14, for displacing the steering axle 13 in the corresponding direction. Springs 17 are arranged between the bearing 11 and the forked end 16' of the frame rod 16 in order to limit the motion of the axle 13 and to assist in returning the frame 1 10 to its normal horizontal condition.

For braking, the skater presses down with the heel the back portion of the plate 5, causing the latter to pivot around the pin 6. By this movement a tractive effort on the brake bands 8 is 15 produced so as to bring the latter into contact with the brake drums 7.

It will also be noted that the toothed segments 14, 15 of the steering device may be replaced by a forked extension terminating the rod 16 and having arms 18 and 16a disposed so as to bear against and actuate the steering axle 13 on one side or the other of the vertical pin 12, according as the frame 1 is inclined by the skater towards the right or the left. (Figs. 5, 6.)

Having thus described my present invention, what I now claim and desire to secure by Letters Patent is:

1. In a roller skate having forward wheels and a rear wheel, the combination of a laterally swinging frame, means actuated by said frame for steering the forward wheels of the skate, a longitudinally tiltable plate resting on said frame and actuated by the heel of the skater, means actuated by said plate for braking the skate, and means to prevent the skate from running backwards.

2. In a roller skate, a laterally swinging frame, means actuated by said frame for steering the skate, a longitudinally tiltable plate secured to 40 the boot of the skater, and resting upon said frame, a pin secured to the said frame and on which the said plate may tilt, means actuated by said tiltable plate for braking the skate, and means to prevent the skate from running back- 45 wards.

3. In a roller skate, a laterally swinging frame, a rod connected to said frame having a forked end projecting upwardly, a toothed segment carried by said forked end, a second toothed segment engaged with the first toothed segment, a vertical pin carrying said second toothed segment and carried by the wheel axle, a bearing member receiving said vertical pin and comprising a rod on which the frame may swing whereby the skate 55

may be steered, a longitudinally tilttable plate secured to the boot of the skater and resting upon said frame, means actuated by said plate for braking the skate, and means to prevent the skate from running backwards.

4. In a roller skate, a laterally swinging frame, a rod connected to the said frame having a forked end, a vertical pin carried by the wheel axle, said forked end engaging the wheel axle on one side

of the said vertical pin, a bearing member receiving the said vertical pin and comprising a rod on which the frame may swing, whereby the skate may be steered, a longitudinally tilttable plate secured to the boot of the skater and resting upon said frame, means actuated by said plate for braking the skste, and means to prevent the skate from running backwards.

RAPHAEL CLEDINA.
